UNITED STATES PATENT OFFICE

2,150,670

BLOWER

Oliver D. H. Bentley, Norfolk, Mass.

Application April 8, 1938, Serial No. 200,933

3 Claims. (Cl. 230—116)

This invention relates to blowers and relates more particularly to turbine driven blowers assembled as units.

On naval vessels, for example, such as destroyers, it has been the practice in the past, in providing forced draft for the boiler furnaces, to draw in atmospheric air through deck ventilators and to force it under considerable pressure into the boiler rooms. This is no longer desirable for the reason that it is expected that in future naval engagements, poison gas bombs will be dropped by hostile air-craft, and the former practice in providing forced draft would result in the poison gases being forced by the blowers, into the boiler rooms to affect the engineers and other attendants.

The present invention provides a deck supported turbine driven blower, the outlet of which may be connected directly to a boiler so that the air supplied by the blower cannot escape into the boiler room. This is accomplished by an efficient, compact design which enables the device to fit in advantageously with but slight departure from existing boiler room design practices.

An object of this invention is to provide a deck supported, forced draft blower, the outlet of which may be connected to a boiler casing.

Another object of the invention is to provide a turbine driven blower with a flexible shaft between the blower and turbine for turning the air delivered by the blower.

Other objects of the invention will be apparent from the following description taken together with the drawing.

The invention will now be described with reference to the drawing, of which:

Fig. 1 is a side view with a portion in section, of one embodiment of a turbine driven, deck supported blower according to this invention, and

Fig. 2 is a plan view, looking downwardly, in reduced scale, of the blower of Fig. 1.

The blower and turbine are assembled as a unit and are adapted to be mounted with drive shaft vertical as shown by Fig. 1. The upper end of the assembly is adapted to be bolted to the deck plates of a ship as by the bolts 5, with the inlet passage 6 of the blower in alignment with an opening in the deck.

The turbine indicated generally by the numeral 1 is of standard design and will not be described in detail.

The turbine 1 is supported from the deck of the ship by means of the tubes 8 which are bolted to the deck of the ship by the bolts 5 and to the turbine assembly by the bolts 9. The rotor 13 of the

turbine is mounted on the rotary shaft 10 adjacent the lower end thereof.

Mounted on the upper end of the shaft 10 is the blower hub 11 on which are formed the propeller blades 12. The hub 11 is streamlined for the efficient flow of air. The shaft 10 is journaled to revolve in the sleeve bearings 14. The inner ends of the brace arms 15 are attached to the journal 16 of the bearings 14 and their outer ends are clamped around the rods 8.

The inner casing 17 extends around the greater portion of the journal 16 and around substantially the entire portion of the shaft which is exposed to the air stream moved by the blades 12. The hub 11 and casing 17 are designed to cooperate in providing a stream-lined enclosure for the shaft 10 and the journal 16. The casing 17 is supported on the arms 15 which extend through it.

The assembly is also provided with the upper 20 casing 3 which provides vertically downward air flow through the blower and the outer casing 18 which forms an elbow type passage below the journal 16 and between it and the turbine 1. The casings 3 and 18 are bolted together at 4. The 25 lower portion of the casing 18 has the flange portion 19 for attachment to a boiler casing. The casing 18 turns the air through an angle of substantially 90° and enables the air to be supplied to the boiler in a path avoiding the turbine 1. 30

In order for the casing 18 to provide an adequate air passage between the blower and turbine, the shaft 10 is made relatively long and its portion between the journal 16 and the upper portion of the turbine 8 has a reduced diameter to provide a 35 degree of resiliency to compensate for any slight misalignment in the assembly and to simplify the bearing design. This form of shaft is known as a quill shaft.

While one embodiment of the invention has 40 been described for the purpose of illustration, it should be understood that the invention is not limited to the exact apparatus and arrangement of apparatus described, as many departures may be suggested by those skilled in the art, without 45 departing from the spirit of the invention.

What is claimed is:

1. A blower assembly adapted to be supported from the deck of a marine vessel, comprising a substantially vertical shaft, a blower mounted on 50 said shaft adjacent the upper end thereof, a motor adjacent the lower end of said shaft and having its rotor mounted on said shaft, a plurality of vertical supporting members, each attached at one end to said motor and adapted to be attached at 55

the other end to said deck, a bearing around said shaft adjacent said blower, means for supporting said bearing from said members, and an air guiding casing supported from said members, said casting having an upper cylindrical portion and a lower elbow type portion between said blower and said motor shaped to turn the air from said upper portion through a substantial angle, the portion of said shaft between said bearing and said motor having a reduced diameter for providing resiliency to compensate for any misalignment in said assembly.

2. A blower assembly adapted to be supported from the deck of a marine vessel, comprising a substantially vertical shaft, a blower mounted on said shaft adjacent the upper end thereof, a motor adjacent the lower end of said shaft and having its rotor mounted on said shaft, a plurality of vertical supporting members, each attached at one end to said motor and adapted to be supported at the other end from said deck, a bearing around said shaft adjacent said blower, means for supporting said bearing from said members, and an air guiding casing supported between said members, said casing having an upper cylindrical portion and a lower elbow type portion between said blower and said motor shaped to turn the air from said upper portion through a substantial angle, the portion of said shaft between said bearing and

said motor having a reduced diameter for providing resiliency to compensate for any misalignment in said assembly.

3. A blower assembly adapted to be supported from the deck of a marine vessel, comprising a substantially vertical shaft, a blower mounted on said shaft adjacent the upper end thereof, a motor adjacent the lower end of said shaft and having its rotor mounted on said shaft, a plurality of vertical supporting members, each attached at one end to said motor and adapted to be supported at the other end from said deck, a bearing around said shaft adjacent said blower, means for supporting said bearing from said members, an air guiding casing supported between said members, said casting having an upper cylindrical portion and a lower elbow type portion between said blower and said motor shaped to turn the air from said upper portion through a substantial angle, a streamlining casing around said bearing below said blower and said shaft within and spaced from said air guiding casing, and means for supporting said streamlining casing from said members, the portion of said shaft between said bearing and said motor having a reduced diameter for providing resiliency to compensate for any misalignment in said assembly.
